UNITED STATES PATENT OFFICE.

PETER PACE, OF ROCHESTER, NEW YORK.

HIGHWAY BARRIER FOR RAILROAD CROSSINGS.

Application filed February 23, 1923. Serial No. 620,622.

To all whom it may concern:

Be it known that I, PETER PACE, a citizen of the United States, residing at Rochester, in the county of Monroe and State of New York, have invented certain new and useful Improvements in Highway Barriers for Railroad Crossings; and I do hereby declare the following to be a full, clear, and exact description of the same, reference being had to the accompanying drawings, forming a part of this specification, and to the reference numerals marked thereon.

My present invention relates to railroads and means for protecting highways crossing the same and it has for its object to provide a simple, convenient and effective barrier or gate for the highway that can be operated with ease and certainty to safely warn vehicles of the approach of a train and to prevent them from proceeding on to the track. The improvements are directed in part toward providing a gate of this nature that will yield sufficiently when struck by a vehicle to avoid damage to itself and to the vehicle. To these and other ends the invention resides in certain improvements and combinations of parts all as will be herein-after more fully described, the novel features being pointed out in the claims at the end of the specification.

In the drawings:

Figure 1 is a plan view of a railroad of a highway crossing the same and provided with automatic barriers constructed in accordance with and illustrating one embodiment of my invention;

Figure 2 is an elevation of the gate mechanism partly in section and taken in transverse section through the road bed of the highway, the gate being in lowered or normal position.

Figure 3 is a similar view with the gate in raised or danger position.

Figure 4 is a vertical section taken on the line 4—4 of Figure 2.

Figure 5 is a detail section on the line 5—5 of Figure 3 showing the manner in which the gate may yield laterally.

Figure 6 is an enlarged fragmentary elevation of the upper end of the gate.

Figure 7 is an enlarged transverse section of the valve mechanism controlling the pneumatic operating means for the gate.

Figure 8 is a plan view of such controlling mechanism.

Figure 9 is a detail side elevation of the

actuator mounted on the railroad track for opening the gate and

Figure 10 is a detail showing the position of the closing actuator.

Similar reference numerals throughout the several views indicate the same parts.

To first give a general idea of the principal elements of the apparatus I provide the highway at opposite sides of the railroad with preferably vertically movable gates located in pits or wells and normally retracted below the surface of the road bed. Pneumatic or hydraulic means are provided for raising and lowering these gates under the control of a valve actuated by an approaching train through devices located on the tracks. In the present instance, the gates are also pivoted to swing laterally so that if struck by a vehicle they will yield, yielding retaining devices being employed to hold them upright. Referring more particularly to the drawings, 1 and 2 indicate the rails of a railroad crossed by a highway the road bed of which is indicated at 3. At suitable distances from the track on each side there is provided in the road bed a transversely extending well 4 the sides of which toward the edges of the road are flanked by preferably tubular guide posts 5. On the inner sides of the posts are grooves 6 constituting guide ways that receive trunnions or projecting pins 7 on the ends of a gate frame 8. The gate is of suitable height to offer a barrier for an ordinary road vehicle, is preferably composed of netting as indicated at 9 and normally occupies the lower position of Figure 2 at the bottom of the guide 6 with its upper edge level with the surface of the road bed.

Within the pit 4 between the posts and below the gate is a cylinder 10 containing a piston 11 on a rod 12 extending through the upper head 13 of the cylinder and through a transverse bar 14 connecting the posts 5 and resting on the top of the cylinder (there being a similar bar 15 connecting the posts below upon which bar the cylinder rests). The upper end of the rod carries a transverse bar 16 provided with a pintle 17 the ends of which travel in the guideway 6 in the manner of the trunnions 7. The pintle is received in knuckles 18 on the bar 16 and on the lower rail of the gate frame respectively. When the gate is elevated in the manner hereinafter set forth from the position of Figure 2 to the operative position

of Figure 3, the trunnions 7 reach the upper ends of the guide posts where the guideways 6 are provided with laterally turned outlets 19 as shown in Figures 4, 5 and 6. Leaf 5 springs 20 restrict these lateral extensions or outlets so that the trunnions 7 will not normally escape but when force is used as by the impact of a vehicle the trunnions are forced past the retaining springs and the gate is 10 permitted to swing downwardly upon the road bed allowing the vehicle to pass over without substantial damage to either it or to the gate. The necessity for this action might arise were the gate to come up suddenly 15 in front of a vehicle but did not have time to stop entirely before reaching it. The vehicle would nevertheless have been warned and could stop in time to avoid being struck by the train.

20 Spectacle lights 21 may surmount the posts 5 to give warning of their operation and act as beacons at night. They are suitably supplied from wires 22 running from the pit up through the hollow posts.

25 It will be seen from the foregoing that pneumatic or hydraulic pressure introduced through a pipe 23 into the bottom of the cylinder 10 below the piston 11 will force up the plunger rod 12 and elevate the gate. 30 It will descend of its own weight when this pressure is released and it is in this way that the gate is operated and controlled. The source of pressure supply is herein represented by a tank 24 from which a pipe 25 leads to a conveniently located valve casing 26 having further connection at 27 with the pipes 23. Also running from the latter at 28 back through the valve casing 26 in a relatively transverse direction and emerging 35 at 29 is an exhaust line having a discharge point at 30. A rotary valve member 31 in the valve casing as will be seen from Figure 7 turns through 90 degrees to close the pressure line and open the exhaust line as shown 40 in full lines or the reverse and the position of the gates is thus determined.

45 The valve 31 is on a shaft 32 projecting through the top of the valve casing 26 and provided with a pinion 33. The said pinion meshes with a rack bar 34 movable in a suitable guide 35 carried by a bracket mounted on the valve casing. Bell cranks 36 pivoted at 37 and having slotted connection at 38 with the rack bar are adapted to move the latter in opposite directions to open and close the valve. Connected to the two bell cranks respectively are pull rods 39 and 40, the former extending down the track in the direction from which the train approaches 50 and being connected to a trip 40 pivoted at 41 to one of the rails as shown in Figure 9. The other pull rod is connected similarly to another trip 42 pivoted at 43 to the rail beyond the crossing.

55 The normal positions of these trips is as

shown in full lines in Figure 9 and in the lower dotted line position in Figure 10. An approaching train depresses the trip 40 pulling the rod 39 and opening the valve 31 to the dotted line position of Figure 7. This supplies pressure to the gates and at the same time raises the trip 42 to the upper dotted line position of Figure 10. The gates remain raised until the train passes the crossing and reaches the trip 42 which it depresses rotating the valve 31 to the full line position of Figure 7 and allowing pressure in the cylinder 10 to escape through the exhaust line 28-29 with a consequent lowering of the gates. The original position of the trip 40 is restored ready for actuation by a succeeding train.

As before stated, the pressure medium may be either air or water and obviously the gate itself may be of any desired design or construction.

I claim as my invention:

1. In a highway crossing barrier for railroads, the combination with a railroad and a highway crossing the same and provided with a pit adjacent to the railroad, of a vertically movable gate normally retracted within the pit below the surface of the highway, pneumatic operating means for raising the gate to bar the highway and lowering the same, and a controlling device for the operating means embodying a trip arranged on the railroad to be actuated by an approaching train.

2. In a highway crossing barrier for railroads, the combination with a railroad and a highway crossing the same and provided with a pit adjacent to the railroad, of a vertically movable gate adapted to bar the highway and normally retracted within the pit below the surface of the highway, posts at the sides of the pit provided with guides for the gate, a cylinder and piston in the pit below the gate, the piston rod supporting the gate, pressure and exhaust pipes connected to the cylinder, a valve controlling the same and train operated trips on the railroad for actuating the valve.

3. In a highway crossing barrier for railroads, the combination with a railroad and a highway crossing the same and provided with a pit adjacent to the railroad, of a vertically movable gate normally retracted within the pit below the surface of the highway, pneumatic operating means for raising and lowering the gate, a rotary valve controlling the same, a pinion on the valve, a rack bar meshing with the pinion, levers for moving the rack bar in opposite directions, pull rods on the respective levers and trips on the railroad on opposite sides of the highway respectively connected to the levers and adapted to be actuated by a passing train to raise and then lower the gate.

PETER PACE.
